MECHANICAL TOY

Samuel I. Berger, Newark, N. J.

Application February 2, 1938, Serial No. 188,235

13 Claims. (Cl. 46—107)

My present invention relates more particularly to mechanically operated toys capable of locomotion, and while certain aspects thereof are of wider application to toys generally of this type, 5 the invention is applicable more especially to spring motor driven toy vehicles.

One object of the present invention is to provide a toy of the above type, which automatically makes at predetermined intervals a sharp pivotal 10 turn to change the direction of locomotion of the toy.

Another object is to provide a toy of the above type, which automatically follows a succession of straight courses and which at predetermined intervals makes a pivotal square or pivotal 15 reverse turn.

Another object is to provide a toy of the character described having a certain predetermined locomotive movement, which gives the impression of being intended and pre-designed, in contra-distinction to the usual spring motor toy having a haphazard uncertain travelling movement.

Another object is to provide a self-propelled 20 toy, which makes at predetermined intervals a sharp pivotal turn, always in the same rotative direction, so that the movement of the toy is confined within a restricted area.

Another object is to provide a toy of the character described which in its realistic appearance 30 and action will be intriguing and highly appealing to the imagination of a juvenile operator, and which is simple, efficient, rugged and durable in use, and yet well-suited to the requirements of economical manufacture.

The invention is shown embodied in a toy military 35 tank, characterized when in operation by its realistic simulation of a full-sized military tank in combative locomotion.

In the accompanying drawings in which is 40 shown one of various possible embodiments of the several features of the invention.

Fig. 1 is a top plan view of a toy military tank, constructed in accordance with the present invention.

Figs. 2 and 3 are sections taken respectively on lines 2—2 and 3—3 of Fig. 1, but shown on a somewhat larger scale.

Fig. 4 is a section taken on line 4—4 of Fig. 2.

Fig. 5 is a section taken on line 5—5 of Fig. 4.

Figs. 6 and 7 are sections taken respectively on lines 6—6 and 7—7 of Fig. 2, and

Fig. 8 is a bottom plan view of the traction wheel section of the tank.

Referring to the drawings, the invention is 55 shown embodied in the form of a toy military

tank, comprising upper and lower similar metal sheets 11 and 12, suitably interlocked at 13 and following the contour of ovate spaced side metal plates 14 and 15 to which said sheets are joined preferably by the ordinary slot and bendable tongue connections 16 well known in the toy art. The resultant chassis assembly simulates the armor of a tank and defines a curved forward end 17, a narrower rear end 18, and a straight bottom 20, (Fig. 2).

Connected preferably by the usual tongue and slot connections to the top side of the armor casting is an inverted cup-shaped member 22, simulating a gun turret. Connected to the forward side of this turret 22 preferably by slot and tongue 15 connections is a tubular member 23 rolled from a thin metal sheet to simulate a gun barrel.

The power plant comprises a simple spring motor M mounted within the chassis, and resting on the bottom plate section 20 thereof. This motor 20 is set between a pair of spaced frame plates 25 and 26, joined to provide a casing therefor, plate 25 having transverse extensions 19 affording the tongues for slot and tongue connections with the armor plate 14. These frame plates 25 and 26 25 form journals for a winding shaft 27, one end 27a of which extends through an aperture 28 in the side plate 14 and is polygonal in cross-section to receive a winding key 27b.

Mounted on the winding shaft 27 for rotation 30 therewith is a ratchet plate 28 (Figs. 4 and 5) having prongs 30 cooperating with detent slots 31 in main spur gear 32, loosely supported on said shaft. Affixed to the winding shaft 27 is one end 35 of a powerful motor spring 35, the other end 36 35 being anchored to an end frame plate 37 forming an integral part of one of the frame plates as for instance, plate 26.

Journalled on frame plates 25 and 26 is a wheel axle 38, driven from main gear 32 by a pinion 40a 40 (Fig. 4) affixed to said axle and meshing with said gear.

In the winding of the spring motor, the rotation of the winding shaft 27 in a counterclockwise direction as viewed in Fig. 5, causes the winding 45 of the motor spring 35 about said shaft, the ratchet prongs 30 riding idly past the detent slots 31 of gear 32 during this operation. When winding shaft 27 is released, the potential energy stored in the wound spring 35 rotates said shaft 50 in a clockwise direction, and the resultant catching of the prongs 30 in the detent slots 31 effects the rotation of the wheel axle 38 in forward driving direction.

The axle rod 38 has affixed thereto near the 55

inner side of the plates 14 and 15, a pair of traction wheels 40 and 41 extending partially through slots 42 and 43 respectively in the chassis plate 12 and almost concealed from view.

5 Centrally connected to the forward end of the chassis is a caster wheel 45, (Figs. 2 and 7) mounted on an axle pin 46, supported on a swivelling bracket 47. This bracket 47 has a pair of spaced arms 48 on which the axle 46 is supported and a pair of spaced flanges 50. These flanges 50 straddle a pair of spaced flanges 51, extending rearwardly from a hinge post 52 affixed to chassis plate 12 preferably by tongue and slot connections, and are pivotally connected to said 15 flanges 51 by a pintle 53.

Wheel 45 extends partially through a segmentally shaped slot 54 in the chassis plate 12 so that it rides idly on the floor F, and is free to swivel in accordance with the pivotal movement of the toy. 20 One end 55 of the slot 54 is advantageously parallel to the longitudinal median plane of the toy, and the other end 56 is at right angles thereto for the purpose hereinafter made apparent.

25 As an important feature of the present invention, the means for pivoting the toy in its sharp turn movement includes a lever 61 (Figs. 3 and 4), pivotally connected to the frame plate 25 at 60, and having an extension 62 at one side of its lower end projecting through a slot 63 formed in 30 an outward flange 64 on the lower edge of said frame plate. This extension 62 terminates in a point 65 and serves as a pivot leg for the toy as will be hereinafter made apparent.

35 The upper end 66 of the lever 61 extends through a guide slot 67 formed in an outward flange 68 of frame plate 25, and is provided just below said flange with a transverse extension 70, cooperating as a follower with a cam 71 affixed to winding shaft 27. The lever 61 is urged in a 40 counterclockwise direction as viewed in Fig. 3 about its pivotal support 60 by means of a U-shaped spring clip 72 straddling the motor casting, and having its bent base portion 72a anchored in corners formed between the lower edges 45 of frame plates 25 and 26, and lugs 75 depending from said plates respectively. One side arm 72b of spring clip 72 passes over a fulcrum piece 73 struck out from the frame plate 25, and underneath a tongue 74 struck out from the lever 61, 50 so that this arm will be curved downwardly to impart spring tension to lever 61 in a counterclockwise direction. The other side arm 72c (Fig. 2) of spring clip 72 is similarly retained in tensioned position as will hereinafter be made apparent.

55 The lower end of lever 61 (Fig. 8) extends through a narrow opening 76 in the bottom chassis plate 12 forming a central offset from the slot 42, and the lever 61 is so positioned and so shaped that the pivot leg 62 is directly below wheel axle 38 and passes through said opening 76. For that purpose the lower portion 78 of the lever 61 is substantially triangular, and the edge 79 of pivot leg 62 is convexly curved so that said edge 65 will lie closely adjacent to the wheel axle 38 and pivot point 65 will lie directly below said axle. In the position shown in full lines in Fig. 3, while the low part of the cam 71 is opposite follower plate 10, pivot point 65 will be above the lower 70 peripheries of wheels 40 and 41, and in the dotted position shown, pivot point 65 will extend below the lower periphery of said wheel 40.

75 In the operation of the turning feature of the invention, as cam 71 rotates in a counterclockwise direction (Fig. 3) by the unwinding action of

motor spring 35, lever 61 will be angularly oscillated about its pivot support 60. When the high part of the cam 71 rides over follower plate 10, pivot leg 62 will come down into dotted position shown in Fig. 3 and tilt the toy on one side so that the wheel 40 will be above the floor and will have no tractive effect on said toy. The toy will then pivot about the pivot point 65 as the result of the tractive action of wheel 41. As soon as the toy starts to pivot the circular drag of the floor on 10 caster wheel 45 causes said wheel to swivel from the position shown in Figs. 2 and 7, to a position at right angles thereto so that this wheel in its new position aids in the continued pivotal movement of the toy. The end 56 of segmental slot 54 15 serves as a stop for caster wheel 45 so that said wheel will not quiver and will be maintained in proper steady position during turning movement of the toy.

When the high part of cam 71 has rotated past 20 engagement with follower plate 10, lever 61 under the action of the spring 72 will return to its normal position shown in full lines in Fig. 3 and the pivot leg 62 will be lifted to restore the wheel 40 into driving engagement with the floor. The toy 25 will then resume its straight course, and caster wheel 45 will be dragged to the position shown in Figs. 2 and 7 in the median longitudinal plane of the toy.

30 Cam 71 is so designed, and its speed of rotation so correlated with the speed of rotation of wheels 40 and 41 that the toy will make a square turn. That is the pivot leg 62 will remain in pivot position long enough for the toy to turn 90°. However, as far as certain aspects of the invention 35 are concerned the cam 71 may be constructed to impart a pivotal turning rotation of any desired angle. The return movement of pivot leg 62 may for instance, be delayed long enough to permit the toy to reverse itself at predetermined intervals.

35 It must be noted that the lever pivot connection 60 is substantially in the horizontal plane of pivot point 65, and that the distance between said pivot connection 60 and said pivot point is sufficiently 45 great so that said pivot point 65 has a substantially vertical movement. In this manner, pivot point 65 does not substantially change its position during turning action of the toy and the turning will therefore be a true pivotal one.

40 The toy is also provided with a housing 80 (Figs. 1 and 2) connected to the top of the armor plate 11 preferably by the usual slot and tongue connections, and having a substantially rectangular opening 81 at the top simulating the entrance or exit opening of the tank. Connected to the housing 80 at the rear end of opening 81, is a pintle 82 to which is supported a door 83. Connected to the underside of door 83, preferably by slot and tongue connections, is an elongated 60 U-shaped bracket 84 affording at its forward end, a pair of spaced ears 85 to which is pivotally connected at 87 a figure 86 simulating a soldier in firing or gun sighting position. This figure 86 is 65 preferably formed by a pair of similar dished sections joined together by overlapping tongues, and has its center of gravity forwardly of its pivotal support 87.

70 The figure 86 and the door 83 are operated intermittently from the spring motor M in such a way, that the door 83 will swing into closed position, and the figure 86 will enter the interior of the tank during one operating phase, and during another phase, the door will open and the figure 86 will swing out through the opening 81 into fir- 75

ing position shown in Fig. 2. For that purpose, the rear end of bracket 84 has a lug 88, to which is pivotally connected one end of a wire pitman 90, the other end being pivotally connected at 88 to a lever 91 which is pivotally supported at 92 to frame plate 26. This lever 91 has pivotally connected thereto at 93, a cam follower 94 having a pair of follower flanges 96 and 96a which are adapted to cooperate consecutively with a cam 97 fixed to the winding shaft 27, and which are substantially at right angles to each other. The lever 91 is supported between cam 97 and frame plate 26, and in order that the winding shaft 27 does not interfere with the swinging movement of said lever, said shaft passes through an elongated slot 98 formed in said lever.

The lever 91 is urged in a clockwise direction as shown in Fig. 2 by the spring clip 72. For that purpose the spring side arm 72c passes over a fulcrum piece 101 struck out of plate 26 and underneath an offset detent 102 formed in cam follower 94, and is downwardly curved in tensioned position to urge said follower 94 in a counterclockwise direction (Fig. 2) about its pivotal support 93 with respect to lever 91. The extent of counterclockwise movement of follower 94 with respect to lever 91 is determined by an outwardly struck lug 103 of lever 91 serving as a stop for said follower so that when said follower 30 engages said lug said follower and said lever 91 will be urged in unison in a clockwise direction by spring clip 72. In this manner the spring clip 72 serves the dual function of acting upon both levers 61 and 91.

In operation, as winding shaft 27 is turned in counterclockwise winding direction (Fig. 2) cam 97 acting on follower flange 96 will oscillate follower 94 about its pivotal support 93 without disturbing lever 91. During the unwinding operation of spring motor M as winding shaft 27 rotates in clockwise direction (Fig. 2), cam 97 engaging follower plate 96a will oscillate follower 94 and lever 91 in unison about pivotal support 92. While lever 91 is swinging in counterclockwise direction it exerts a downward pull on pitman 90 causing door 83 to open and figure 36 to move from the interior of the tank into firing position shown in Fig. 2. As lever 91 swings back in clockwise direction under the action of spring 72, it exerts an upward force on pitman 90 causing door 83 to swing back again into closed position. During this closing movement, the forward portion 104 of figure 36 riding over the corner 105 of turret 22 or over a downward flange 106 at the forward end of door opening 81 will swing said toy in clockwise direction (Fig. 2) about its pivot support 87, so that this figure will ride smoothly into the interior of the toy chassis.

Associated with gun barrel 23 is a spark generating mechanism operated from the spring motor M to simulate a firing gun. For that purpose, there is journalled in the plates 25 and 26 a shaft 110 (Figs. 2, 4, and 6) carrying a pinion 111 meshing with a gear 112 affixed to axle shaft 38. Connected to one end of this shaft 110 is a crown gear 113, meshing with a pinion 114 affixed to one end of an oblique shaft 115, the other end of which carries a crown gear 116 near the roof of the chassis. The lower end of this shaft 115 is journalled in a flange 117 extending outwardly from the plate 26, and the upper end is journalled in a bracket 118 supported from the roof of the chassis preferably by tongue and slot connections. This bracket 118 has a pair of spaced side members 120 in which is journalled

a shaft 121 carrying a pinion 122 meshing with crown gear 116. Affixed to one end of shaft 121 is a wheel 123 having an abrasive surface, and passing through an opening 124 in the top of plate 11 and a slot 125 in the forward part of the gun turret 22. Resting on the periphery of this abrasive wheel 123 is a pyrophoric element 126 preferably in the form of a flint piece connected to one end of a bar 127, the other end 129, being offset and passing through a slot 128 in the top portion of the gun barrel 23 to pivotally support said bar. By means of this construction, as the vehicle moves, abrasive wheel 123 is rotated in a counterclockwise direction (Fig. 2) thereby generating sparks which fly forwardly through the outlet of the gun barrel 23 in simulation of a firing gun.

The chassis also has incorporated therein a sound producing means for simulating the repeated sounds of a firing gun. This means includes a wheel 130 (Figs. 2 and 4) affixed to axle shaft 38 and having a series of teeth 131 preferably only on one side thereof. Cooperating with this wheel 130 is a clapper spring plate 132 having a portion fixed to plate 12 preferably by rivets 133, and having an offset portion 134 at one end contacting with said wheel. As this wheel 130 rotates, the teeth thereof will strike clapper plate 132 and produce a series of repeated gun firing sounds.

A stop mechanism is provided in the form of a lever 140 (Figs. 1, 2, and 6) pivoted at 141 to the side plate 14, and formed with a tongue 142 which is struck out therefrom and which extends inwardly to engage an offset end 143 of shaft 121. In one angular position of lever 140, tongue 142 engaging offset end 143 of shaft 121 prevents the rotation of said shaft and causes braking of the motor M. In the opposite angular position of lever 140, tongue 142 will be out of the path of the rotating offset shaft end 143 so that the entire mechanism will be free to operate.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent is:—

1. A toy of the self-propelled type including a pair of spaced traction members therefor, a driving motor for said traction members, and a pivot leg adjacent to one of said traction members and oscillated from said motor in a substantially vertical direction to periodically bring the lower pivot point of said leg below the lower traction surface of said latter traction member, whereby said latter traction member is rendered inoperative and the toy pivotally turned about said pivot point.

2. A toy of the self-propelled type including a pair of traction wheels, a driving spring motor for said wheels, a pivot leg adjacent to one of said wheels, affording a pivot point at its lower end, and means operated from said motor for oscillating said leg to move said pivot point in a substantially vertical direction, substantially in the vertical plane of the axis of the latter wheel, and alternately above and below the lower traction surface of said latter wheel, whereby the toy is periodically turned about said pivot point.

3. A toy of the self-propelled type including a pair of spaced traction members therefor, a driving motor for said traction members, and a lever adjacent to one of said traction members, and 5 angularly oscillated from said motor, a pivot extension movable periodically by the oscillatory movement of said lever to below the lower traction surface of said latter traction member to tilt the toy, so that the latter traction member is 10 rendered inoperative and the toy pivotally turned about said pivot extension.

4. A toy of the self-propelled type including a pair of traction wheels therefor, a spring motor for said wheels having a frame casing, a 15 lever pivotally supported on said frame casing near one of said wheels, and defining a pivot point at its lower end, and means operated from said motor for angularly oscillating said lever about its pivotal support to periodically move 20 said pivot point below the lower traction surface of said latter wheel, whereby the toy is tilted and caused to turn about said pivot point.

5. A toy of the self-propelled type including a pair of spaced traction wheels therefor, a 25 spring motor for said wheels, a pivotally supported lever adjacent to one of said wheels and defining a pivot point at its lower end, and means for angularly oscillating said lever about its pivotal support to periodically move said pivot point 30 below the lower traction surface of said latter wheel, and including a cam driven from said motor and engaging said lever.

6. A toy of the self-propelled type including a pair of spaced traction wheels therefor, a 35 spring motor for said wheels, a lever having a pivot leg on one side thereof adjacent to one of said wheels, and pivotally supported at a section spaced a substantial horizontal distance from the lower end of said pivot leg and means operated from said motor for angularly oscillating said lever about its pivotal support to move 40 said end in a substantially vertical direction alternately above and below the lower traction surface of said latter wheel, whereby the toy is periodically turned about said pivot leg.

45 7. A toy of the self-propelled type comprising a pair of spaced traction wheels therefor, connected to a common axle, a spring motor for said wheels, including a frame casing, and a winding shaft supported on said casing and having one 50 end thereof extending through one side of said casing to receive a winding key, and having the other end extending through the other side of said casing, a lever having an extension near one 55 end forming a depending pivot leg substantially in the vertical plane of said axle, and pivotally supported on the latter side of said casing near one of said wheels, and at a section spaced a substantial horizontal distance from the lower 60 end of said pivot leg, said lever having a transverse outward flange integral therewith, and means for angularly oscillating said lever about its pivotal support to periodically move said lower end of said pivot leg below the lower traction 65 surface of said latter wheel, whereby the toy is caused to make a pivotal turn about said pivot leg, said latter means including a cam connected to the latter end of said winding shaft and engaging said flange.

70 8. A toy of the self-propelled type including a spring motor having a frame casing, a pair of members supported on said casing on opposite sides thereof, a pair of cams operated from said motor for oscillating said members respectively, a spring clip straddling said motor casing and 75

urging both of said members against the action of said cams, and means responsive to the oscillatory movement of said members for effecting certain amusing operations of said toy.

9. A toy of the self-propelled type including a spring motor having a frame casing, a pair of levers pivotally supported on said casing on opposite sides thereof, a pair of cams operated from said motor for angularly oscillating said levers respectively, a spring clip straddling said casing and having a pair of side arms engaging said levers respectively to urge said levers against the action of said cams, and means responsive to the oscillatory movement of said levers for effecting certain amusing operations of said toy. 15

10. A toy of the self-propelled type comprising a spring motor having a frame casing, a lever pivotally connected to one side of said casing, said motor including a winding shaft supported on said frame casing and having one end extend 20 through an elongated slot in said lever, a cam on the latter end of said winding shaft, a member yieldably mounted on said lever and having a pair of flanges for engagement with said cam, one of said flanges being adapted to be engaged 25 by said cam during the winding rotation of said shaft, to move said member in one direction with respect to said lever, whereby said lever is immobile during said winding rotation, spring means urging said member in opposite direction, 30 stop means for limiting said latter movement with respect to said lever, the other flange being adapted to be engaged by said cam during the unwinding rotation of said shaft, whereby said lever and said member are angularly oscillated 35 in unison about the pivotal support of said lever during this unwinding operation, and means responsive to the oscillatory movement of said lever for effecting an amusing operation of said toy.

11. A toy of the self-propelled type including a motor having a frame casing, a lever pivotally connected to one side of said casing, a winding shaft supported on said frame casing and having one end extending through an elongated slot in said lever, a cam affixed to said shaft end, a member pivotally connected to said lever and having a pair of flanges for engagement with said cam, one of said flanges being adapted to be engaged by said cam during the winding movement of the winding shaft to angularly swing said member in one direction with respect to said lever whereby said lever is immobile during said winding operation, a spring for urging said member in opposite angular direction, stop means for limiting this latter movement of said member with respect to said lever, the other flange being adapted to be engaged by said cam during the unwinding rotation of said shaft whereby said lever and said member are angularly oscillated in unison about the pivotal support of said lever against the action of said spring during this unwinding operation, and means responsive to the angular oscillatory movement of said lever for effecting an amusing operation of said toy. 40 45 50 55 60

12. A toy of the self-propelled type including a chassis having a door, a motor in said chassis having a frame casing, a lever pivotally connected to one side of said motor, said motor including a winding shaft supported on said frame casing and having one end extending through an elongated slot in said lever, a cam on said end, a member pivotally connected to said lever and having a pair of flanges for engagement with said cam, one of said flanges being adapted to be engaged by said cam during the winding op- 70 75

eration of the winding shaft to angularly swing said member in one direction with respect to said lever whereby said lever is not moved during said winding operation, spring means urging said member in opposite direction, stop means for limiting said latter movement of said member with respect to said lever, the other flange being adapted to be engaged by said cam during the unwinding rotation of said winding shaft, whereby said lever is angularly oscillated about its pivotal support, and means responsive to the angular oscillatory movement of said lever for effecting the opening and closing of said door.

13. A toy tank of the self-propelled type including a chassis having an opening on top, and a hinged door for said opening, a figure adapted to extend in and out through said opening, a motor in said chassis including a frame casing, a lever pivotally connected to one side of said motor, a winding shaft supported on said frame casing and having one end extending through an

elongated slot in said lever, a cam on said shaft end, a member pivotally connected to said lever and having a pair of flanges for engagement with said cam, one of said flanges being adapted to be engaged by said cam during the winding operation of the winding shaft to angularly swing said member in one direction with respect to said lever, whereby said lever is not moved during this winding operation, spring means urging said member in opposite direction, stop means for limiting said latter movement of said member with respect to said lever, the other flange being adapted to be engaged by said cam during the unwinding rotation of said winding shaft whereby said lever is angularly oscillated about its pivotal support, and means responsive to the angular oscillatory movement of said lever for effecting the opening and closing of said door and the in and out movement of said figure through said opening.

SAMUEL I. BERGER. 20
